UNITED STATES PATENT OFFICE

2,440,566

FUEL SUPPLY SYSTEM FOR INTERNAL-
COMBUSTION ENGINES

George Jeffrey Armstrong, Farnborough, England

Application February 27, 1945, Serial No. 580,029
In Great Britain June 26, 1943

6 Claims. (CL 123—119)

1

The invention relates to fuel supply systems for reciprocating internal combustion engines in which fuel is injected into an intake manifold along which air is passing to the engine. It is known that in such systems the mass air consumption, i. e. the air consumption measured in units of mass per unit time, and hence the fuel requirements of the engine, are dependent on the absolute pressure and temperature in the intake manifold, the absolute exhaust back pressure and the rotational speed of the engine crankshaft. With most engines having well designed exhaust systems the exhaust back pressure is nearly equal to and varies with atmospheric pressure, and hence atmospheric pressure may be measured instead of exhaust back pressure to control the fuel flow. More particularly the invention relates to such a system in which the flow of fuel is controlled by an adjustable metering valve or valves whose effective flow area is adjusted in accordance with the intake manifold pressure, atmospheric or exhaust back pressure, and it is an object of the invention to provide a means for controlling the pressure difference across the metering valve or valves by an adjustable pressure-reducing valve which regulates said pressure difference in accordance with the square of the engine speed whereby for a given adjustment of the metering valve or valves the flow through said metering valve or valves is made dependent on the engine speed.

In accordance with the invention in a system of the kind hereinbefore specified, the output of a positive displacement pump driven at a speed proportional to engine speed is passed through a passage having a pressure-reducing constriction, e. g. a sharp edged orifice, and the pressure difference across said constriction is applied to a pressure-responsive element which actuates the pressure reducing valve. It will be appreciated that since the flow from a positive displacement pump is proportional to the speed at which the pump is driven, the pressure difference at the two sides of the constriction will be proportional to the square of the engine speed and hence the pressure-reducing valve will be adjusted in accordance with the square of the engine speed so that for a given adjustment of the metering valve or valves the desired proportionality between flow through the metering valve and engine speed will be maintained.

Conveniently, the positive displacement pump is the pump supplying fuel to the engine, and the adjustable pressure reducing valve is a balanced valve whose adjustable member is connected to two diaphragms or like pressure-responsive ele-

2

ments, one of said elements being exposed to the pressure difference across the constriction and the other to the pressure difference across the metering valve or valves, so that the pressure reducing valve is continuously adjusted to provide a relationship between the two pressure differences, which relationship is determined by the relative areas of the two diaphragms or the like.

The invention is illustrated in the accompanying schematic drawings, in which:

Fig. 1 is a sectional view of a system embodying the invention and also incorporating the invention of co-pending British application No. 9250/43 (U. S. Serial No. 580,028).

Fig. 2 is a fragmentary sectional view showing an alternative means of introducing temperature correction.

Fig. 3 is a fragmentary sectional view showing an alternative diaphragm assembly.

Figs. 4 and 5 are views showing alternative arrangements each having two positive displacement pumps connected in series.

Referring to Fig. 1 fuel passes through pipe 10 to a positive displacement pump 11 driven by a shaft 111 from the engine 27a to which fuel is to be supplied, said shaft 111 being the engine accessory driving shaft. From the pump 11 the fuel is supplied to the engine through a sharp-edged orifice 12, passage 13, chamber 14, pressure reducing valve 15, chamber 16, metering valve 17, passage 18, chamber 19 and discharge nozzle 20. The valve 17 comprises an orifice whose effective area is adjusted by a tapering needle 21 connected to a link 22 pivoted at 23 to the wall of a chamber 24 and connected to a link to which are attached resilient bellows 25, 26, bellows 25 being subject internally to the pressure in the intake manifold 27 of the engine 27a, a connecting pipe 28 being provided for this purpose, and bellows 26 being evacuated internally. The inside of chamber 24 communicates with the passage 18 through a port 29 and is filled with fuel in which both bellows are immersed. The fuel in the passage 18 and consequently in the chamber 24 is maintained at a pressure exceeding atmospheric by a predetermined amount by a tapering needle 30 which co-operates with the discharge nozzle 20 and which is anchored to a diaphragm 31, the right hand side of which is exposed to the pressure of the fuel in the chamber 19 and the left hand side of which is backed by a spring 33 and is also acted on by the atmosphere entering through a vent 32. Consequently the needle 30 adjusts the area of the discharge nozzle 20 to cause the pressure of the fuel in the chamber 19 continuously to be at a pressure exceeding atmospheric by a quantity determined

by the stiffness of the spring 33. The arrangement of bellows and adjustable discharge nozzle forms the subject of British application No. 9250/43 and it will be appreciated that this means for producing adjustment of the metering valve 17 forms no part of the present invention and that the present invention may be embodied in systems employing other means for producing such adjustment. The present invention is concerned with the regulation of the pressure difference across the metering orifice 17, and this means will now be described.

The engine driven pump 11 is arranged to have an output exceeding the maximum fuel requirements of the engine at any engine speed, and to provide for conditions in which the fuel requirements are less than the output of the pump 11 a spring-loaded relief valve 34 is provided preferably of balanced type. The whole of the output of the pump 11 is passed through the orifice 12 and the relief valve 34 is accordingly located on the output side downstream of the orifice 12. Since the output of the pump 11 is proportional to the engine speed, the pressure difference across the orifice 12 is proportional to the square of said speed. A tapping 35 is led from the high pressure side of the orifice 12 to chamber 36 sealed by a flexible diaphragm 37 the right hand side of which is acted upon by the pressure existing in the chamber 14, i. e. the pressure at the low pressure side of the orifice 12. The diaphragm 37 is consequently biased by the pressure difference across the orifice 12. Connected to the diaphragm 37 is one end of a link 38 carrying a tapering plug 39 which forms the adjustable member of the pressure reducing valve 15. The link 38 is also connected through a pivoted lever 40 to a further link 41 carried by a second diaphragm 42. The pressure at the left hand side of the diaphragm 42 is that existing in the chamber 16, i. e. the pressure immediately upstream of the metering valve 17 while at the right hand side of the diaphragm 42 the pressure existing is that immediately downstream of the metering valve, a port 43 being provided to admit such pressure to the right hand side of diaphragm 42. Accordingly, when the system is operating, the pressure difference across the orifice 12 applies to the diaphragm 37 a force proportional to the square of the engine speed, and this force is transmitted through the link 38, lever 40 and link 41 to the diaphragm 42 and the pressure reducing valve 15 is thus so adjusted that the flow through the valves causes the forces applied by the diaphragms 37 and 42 to be in equilibrium. Such equilibrium will exist when the pressure differences across the two diaphragms achieve a relationship which is determined by the relative areas of the diaphragms and the relative effective lengths of the arms of the lever 40. The pressure difference across the metering orifice 17 will therefore be maintained proportional to the square of the engine speed. Temperature control may be introduced in a variety of ways, thus in the form illustrated, a bulb 44 filled with liquid is located in the intake manifold 27 and is connected by a capillary tube 45 to a capsule 46 one end of which is fixed and the other end of which is connected to a pivoted arm 47 on which the lever 40 is mounted. Movement of the capsule in response to changes in temperature in the intake manifold will displace the pivot of the lever 40 in relation to the links 38, 41 to which it is connected and will accordingly vary the relationship between the effective lengths of the arms of

the lever 40 and hence the ratio between the square of the engine speed and the pressure difference across the metering orifice.

The system also embodies a slow running device in which fuel from the chamber 14 is fed to passage 18 past a tapered plug 48 anchored to a diaphragm 49, the two sides of which are exposed to the pressures of fuel in the chambers 36 and 14 and on which a tension spring 50 acts to hold the plug 48 away from its seating. As the engine speed increases the pressure difference across the diaphragm 49 rises overcoming the resistance of the tension spring 50 and diminishing the flow of fuel through the slow running device.

Referring to Fig. 2, temperature correction is produced by varying the effective area of the orifice 12 instead of by varying the effective lengths of the arms of the lever 40. For this purpose a tapered needle 60 is pivoted to one end of a pivoted arm 61, the other end of which is moved by a Bourdon tube 62 or like element which responds to changes of temperature in the intake manifold.

Other alternative means of introducing temperature correction are possible, e. g. any of the means described in co-pending British application No. 9250/43. If the temperature correction is effected as shown in Fig. 2 or as in British application No. 9250/43, the capsule 46 shown in Fig. 1 may be retained and made responsive to some other variation for which it is desired to correct or vary the fuel-air ratio. Thus if the capsule 46 were evacuated the pressure difference across the metering valve 17 would become proportional not to the square of the engine speed but to a power of the engine speed differing from the square thereof.

Referring now to Fig. 3, fuel from pump 11 after passing through the orifice 12 is supplied to the engine through passage 13, pressure reducing valve 15, metering valve 17 and passage 18. The effective flow passage of the metering valve 17 is varied by a tapered needle 21 which may be operated by means not shown but which may be analogous to those shown in Fig. 1. The means for adjusting the pressure reducing valve however differs from that shown in Fig. 1. As illustrated in Fig. 3 the pressure reducing valve comprises a tapered plug 39 attached to a link 38 secured to four diaphragms, 317, 37, 137 and 371. Between diaphragms 317 and 37 is a chamber 36 communicating with the upstream side of orifice 12 through a passage 35, while the space 140 between diaphragms 317 and 137 communicates with the downstream side of the orifice 12 through passage 130. The pressure at the right hand side of diaphragm 371 is the same as that at the upstream side of the metering valve 17, while the space between the diaphragms 137 and 371 is filled with fuel at the pressure existing at the downstream side of valve 17, said pressure being transmitted through port 29, chamber 24 and balance tube 124. Diaphragms 317 and 137 are in the nature of flexible walls the fluid forces on which are balanced one against the other by design and in particular by the inclusion of a duct 713. The system will consequently be in equilibrium when the pressure difference across the diaphragm 37, which is proportional to the square of the engine speed, is equal to the pressure difference across the diaphragm 371, which is equal to the pressure difference across the metering valve 17, so that said latter pressure difference is continuously maintained proportional to the square of the engine speed.

In practice the volumetric efficiency of a positive displacement gear type pump may vary with the pressure difference between its inlet and outlet, but this pressure difference may be maintained constant and substantially zero by feeding the inlet of the positive displacement pump from a second positive displacement pump of higher output. Figs. 4 and 5 show two arrangements embodying twin pumps.

In Fig. 4 the pump 11 is fed from a positive displacement pump 70 of higher capacity than pump 11. The output of pump 11 is fed through an orifice 12 into a passage 13 as in Fig. 1 a tapping 35 being taken from the upstream side of orifice 12. The passage 13 also receives fuel direct from pump 70 through orifice 71. A de-aerator 72 of conventional design is provided for de-aeration of the fuel before it enters the pump 11 and passage 13. A spring loaded and balanced relief valve 73 is provided between the passage 13 and the inlet of pump 70, so that if the pressure in passage 13 exceeds atmospheric by more than an amount determined by the spring bias on valve 73 the valve opens and fuel passes from passage 13 to the inlet of pump 70.

In Fig. 5 in addition to the relief valve 73 a second relief valve 74 is provided. This valve has a movable member whose head is acted on by the pressure at the outlet from pump 70 and which is secured to a diaphragm, against which a spring abuts and which as shown is also acted upon by the pressure difference between the outlet of pump 11 (through passage 35 and pipe 75) and the inlet of pump 70. The valve 74 will therefore open when the pressure existing in the outlet from pump 70 exceeds a predetermined relationship with the pressure in the passage 35.

Although no supercharger is shown in the drawings it will be appreciated that the invention may be embodied in a fuel supply system for a supercharged engine.

I claim:

1. A fuel supply system for an internal combustion engine comprising an adjustable metering valve, an adjustable pressure regulating valve in series with said metering valve, an engine-driven positive displacement pump having an outlet duct with a constriction therein located to pass the whole output of said pump, a pressure-responsive element located to respond to changes in pressure difference across said constriction, and a connection between said pressure-responsive element and said pressure regulating valve to control the same in response to changes in the output of said positive displacement pump.

2. A fuel supply system for an internal combustion engine, comprising an engine-driven positive displacement pump for supplying fuel through a duct to said engine, an adjustable metering valve in said duct, an adjustable pressure-regulating valve also in said duct, and in series with said metering valve, a constriction located in said duct between said pump and adjustable valves to pass the whole output of said pump, a pair of diaphragms one of which is located to be acted upon by the pressure difference across said constriction and the other of which is located to be acted upon by the pressure difference across said metering valve, and a connection between said diaphragms whereby the pressure difference across said metering valve is maintained proportional to the pressure difference across said constriction.

3. A fuel supply system for an internal combustion engine, comprising an engine-driven

positive displacement pump for supplying fuel through a duct to said engine, an adjustable metering valve in said duct, an adjustable pressure regulating valve also in said duct, and in series with said metering valve, a constriction located in said duct between said pump and adjustable valve to pass the whole output of said pump, a pair of diaphragms one of which is located to be acted upon by the pressure difference across said constriction and the other of which is located to be acted upon by the pressure difference across said metering valve, and a pivoted lever connecting said diaphragms and also actuating said pressure regulating valve.

10 4. A fuel supply system for an internal combustion engine, comprising an engine-driven positive displacement pump for supplying fuel through a duct to said engine, an adjustable metering valve in said duct, an adjustable pressure regulating valve also in said duct, and in series with said metering valve, a constriction located in said duct between said pump and adjustable valves to pass the whole output of said pump, a pair of diaphragms one of which is located to be 20 acted upon by the pressure difference across said constriction and the other of which is located to be acted upon by the pressure difference across said metering valve, a pivoted lever connecting said diaphragms and also actuating said pressure regulating valves, and a temperature-responsive member carrying the pivot for said lever.

25 5. A fuel supply system for an internal combustion engine, comprising an engine-driven positive displacement pump for supplying fuel through a duct to said engine, an adjustable metering valve in said duct, an adjustable pressure-regulating valve also in said duct, and in series with said metering valve, a constriction located in said duct between said pump and adjustable valves to pass the whole output of said pump, a pair of diaphragms one of which is located to be 30 acted upon by the pressure difference across said constriction and the other of which is located to be acted upon by the pressure difference across said metering valve, a temperature-sensitive member for varying the flow area of said constriction, and a connection between said diaphragms, whereby the pressure difference across said metering valve is maintained proportional to the pressure difference across said constriction.

35 6. A fuel supply system as claimed in claim 2, in which the positive displacement pump is in series with a second positive displacement pump 40 whereby the pressure difference across the first of said pumps is maintained substantially zero.

GEORGE JEFFREY ARMSTRONG.
